LOAD CELL FOR MEASURING LOADS ON STRUCTURAL MEMBERS

Stephen Chriss, 160 Jamison Ave., Toronto 3,
Ontario, Canada

Filed Mar. 14, 1968, Ser. No. 10,980

Term of patent 7 years

Int. Cl. D10—08

U.S. Cl. D52—6

The figure is a perspective view of a load cell for measuring loads on structural members, viewed from the top.

The design illustrated in the figure is symmetrical, and the bottom surface (not shown) is identical to the top surface as shown in the figure.

I claim:

The ornamental design for a load cell for measuring loads on structural members, as shown and described.
